UNITED STATES PATENT OFFICE.

JAMES V. RIDGWAY, OF SUMMIT, NEW JERSEY.

DESIGN FOR A FOB-PLATE.

No. 38,382.

Specification for Design.

Patented Dec. 25, 1906.

Application filed November 22, 1906. Serial No. 344,657. Term of patent 7 years.

To all whom it may concern:

Be it known that I, JAMES V. RIDGWAY, a citizen of the United States, residing at Summit, in the county of Union and State of New Jersey, have invented a new, original, and ornamental Design for a Fob-Plate, of which the following is a specification, reference being had to the accompanying drawing, forming a part thereof.

The accompanying drawing is a front view of a fob-plate, showing my new design.

I claim—

The ornamental design for a fob-plate as shown.

JAMES V. RIDGWAY.
